AUTOMOBILE ANTENNA

Arthur T. Mace, East Cleveland, Ohio, assignor
to The Radiart Corporation, Cleveland, Ohio,
a corporation of Ohio

Application August 3, 1939, Serial No. 288,159

8 Claims. (Cl. 189—26)

This invention relates, as indicated, to vehicle radio antennae, but has reference more specifically to radio antennae which are capable of being extended from the interior of the vehicle in which it is used in conjunction with vehicle radio sets.

The conventional type of extending or telescoping antennae are extended or telescoped from the exterior of the vehicle. This results in inconvenience caused by the necessity of getting in and out of the vehicle to extend or collapse the antennae. Also, due to the limitation of the human reach, the extent of projection of the antennae above the top of the vehicle was restricted. An antenna which is collapsible and extensible from the interior of the vehicle eliminates this restriction and inconvenience, and moreover, has the advantage that it may be collapsed to clear obstructions, such as garage door openings and the like.

The primary object of the invention is to provide a radio antenna of the type described which is quickly and easily collapsible and extensible from the interior of the vehicle on which it is used.

Another object of the invention is to provide a radio antenna of the type described which is economical to manufacture and simple in operation.

A further object of the invention is to provide an antenna of the type described which is resiliently retained in any desired degree of extension and in which efficient electrical connection between the various parts thereof is constantly maintained.

To the accomplishment of the foregoing and related ends, said invention, then, consists of the means hereinafter fully described and particularly pointed out in the claims; the annexed drawings and the following description setting forth in detail certain structure embodying the invention, such disclosed means constituting, however, but one of various forms in which the principle of the invention may be used.

In said annexed drawings:

Fig. 1 is a longitudinal cross-sectional view of a portion of an automobile illustrating an antenna embodying the invention mounted thereon;

Fig. 2 is a fragmentary vertical cross-sectional view of an antenna embodying this invention in collapsed condition;

Fig. 3 is a view similar to Fig. 2, but showing the antenna partially extended;

Fig. 4 is a view similar to Fig. 3, but showing the antenna in the next step of extension;

Fig. 5 is an enlarged cross-sectional view of the open position of the collet device used in this invention;

Fig. 5a is a section on line a—a of Fig. 5.

Fig. 6 is a view similar to Fig. 5 but with the collet in locked position;

Fig. 7 is a view similar to Fig. 4, but showing the antenna fully extended;

Fig. 8 is an enlarged vertical cross-sectional view showing a modification of the collet device shown in Figs. 5 and 6; and

Fig. 9 is a fragmentary enlarged view of Fig. 2.

Referring more particularly to the drawings, there is illustrated a portion of an automobile having a hood 1, dashboard 2, windshield 3 and top 4.

A lead-in member 5, which comprises the base of the antenna is attached at one end by any suitable means to the dashboard 2 and at its other end supports by a metal to metal contact the innermost tubular metallic member 6 of the antenna which is slightly peened over at its upper end to provide an inwardly extending retaining flange 7.

Snugly fitting around tube 6, and projecting thereabove is metallic tubular member 8, the lower end of which is attached as by threads 9 to a washer-like member 10 having a rounded peripheral edge 11, and having a hole 12 therein, the purpose of which will be hereinafter described. The upper end of tubular member 8 is of reduced diameter and is split longitudinally to provide a plurality of collet jaws 13, the purpose of which will presently appear.

Snugly fitted around tube 8 is a third metallic tubular member 14, the upper end of which constitutes a collet 15. The lower end of tube 14 is attached as by threads 16 to a washer-like member 17 which has a curved outer end. A pin 18 is secured to the washer 17 and projects downwardly into the washer 10, being provided with a head 18a which is movable in the recess 12 of the latter. Surrounding pin 18 is a coil spring 19 which normally urges the washers 10 and 17 apart.

Snugly fitting around tube 14 is the outermost metallic tubular member 20 which snugly passes through the insulator 21 which is secured in the front of the top of the vehicle and constitutes the second support for the antenna. Suitably attached to the lower end of the tube 20 is a finger knob 22. The upper end of the tube 20 is reduced in diameter to form neck 23, which snugly fits around and guides the wire 24 which forms the uppermost portion of the antenna.

Wire 24 passes through collet 15, collet jaws 13, projects into the innermost tube 6 and has a looped lower end 25 which bears against the inner walls of tube 6 and which is capable of passing through the flange 7. Attached to the upper end of wire 24 is a small metallic ball 26.

Operation

Assuming the antenna embodying the inven-

tion is collapsed, as shown in Figs. 1 and 2, to extend the antenna from the interior of the vehicle the finger knob 22 is raised to the position shown in Fig. 4, causing the outermost tube 20 and consequently the wire 24 to rise correspondingly. By forcing washer 17 closer to washer 10 against the force of spring 19, the collet 15 locks the wire 24 in the collet jaws 13, as shown in Fig. 6, so that if, while so locked, the tubes 8 and 14 are elevated to the position shown in Fig. 7, the wire 24 is forced or pushed up through neck 23 and loop 25 passes through the flange 7 of the stationary tube 6.

To collapse the antenna from the interior of the vehicle the collet, as shown in Figs. 6 and 7, is locked, while tubes 8 and 14 are lowered, causing the antenna to be contracted to the condition shown in Fig. 4. With the collet opened, the tubes 8 and 14 are raised as in Fig. 3, the collet then locked and the three tubes 8, 14 and 20 lowered, effecting the original collapsed arrangement shown in Figs. 1 and 2.

A construction alternative to the collet arrangement shown particularly in Figs. 5, 5a and 6 is illustrated in Fig. 8, wherein the tube 8^a corresponds to tube 8 in the prior figures and has immediately below its upper end a plurality of holes 27 and 28 which accommodate steel balls 29 which encircle tube 8^a. Snugly fitted around tube 8^a is tube 14^a, the upper end of which is bulged as at 30 to house the balls 29. Surrounding tube 14^a is tube 20^a, which snugly fits around bulge 30 and whose upper portion is reduced in diameter to form a neck 31 similar to neck 23 of tube 20.

In the alternative construction shown in Fig. 8, by lowering tube 14^a with respect to tube 8^a, the bulge 30 forces the balls 29 against the wire 24 thereby locking said wire as effectively as with the collet construction which has been described.

Since each tube constitutes a snug fit over its adjacent tube, loop 25 bears against the inner walls of tube 6, and neck 23 snugly fits around wire 24, an efficient electrical contact is constantly maintained and the antenna is resiliently retained in any desired degree of expansion and is rattle-proof.

It is to be noted that the expansion and collapsing can be quickly accomplished entirely from the interior of the vehicle with but a minimum of effort and by the use of but one hand.

Other modes of applying the principle of my invention may be employed instead of the one explained, change being made as regards the structure herein disclosed, provided the means stated by any of the following claims or the equivalent of such stated means be employed.

I therefore particularly point out and distinctly claim as my invention:

1. A device of the character described comprising an inner supporting tube, an outer tube, two intermediate tubes, all of said tubes being nested each of said tubes having one end open and being independently movable with respect to each other, and an element projecting through said openings, said end of one of said intermediate tubes forming collet jaws and said end of the other of said intermediate tubes forming a complementary collet whereby said element may be locked by said jaws and moved with respect to said outer tube.

2. A device of the character described comprising an outer and two inner nested tubes, each having one end open, an element projecting

through said open ends, jaws on one and a collet on the other of said inner tubes whereby said element may be locked by said jaws and moved with respect to said outer tube.

5 3. A device of the character described comprising an outer and two inner nested tubes, each having one end open, an element projecting through said open ends, one of said inner tubes having jaws formed on said end thereof for engaging said element and the other of said inner tubes having a collet formed on said end thereof for actuating said jaws whereby said element may be locked by said jaws and moved with respect to said outer tube.

10 4. The combination of a tube both ends of which are open, an elongate element projecting into one of said ends, movable means projecting into the other of said ends and presenting elastic jaws adapted for clampingly engaging and disengaging said elements, an annular movable means to compress said elastic jaws whereby movement of said first-mentioned means moves said element relatively to said tube.

15 5. In a device of the character described, the combination of a tube having two openings, an elongate element projecting into one of said openings, means including a pair of movable elongate members projecting into the other of said openings, said elongate members having their ends formed to clampingly engage and release each other when moved relatively to each other thereby clamping and unclamping said element, and means for urging said elongate members into unclamping position.

20 30 6. In a device of the character described, the combination of four independently movable tubes each having one end open, an element projecting into said open ends, means for moving the three outer tubes and said element relatively to the innermost tube, and means within the outermost tube responsive to relative movement of the intermediary tubes for gripping said element whereby movement of the intermediary tubes relatively to the outermost tube moves said element relatively to said outermost tube.

25 40 7. In a device of the character described, the combination of independently movable nested tubes the innermost tube of which is adapted to be stationarily mounted, there being three tubes surrounding said innermost tube, all of said tubes having one end open, the two inner of said three tubes projecting beyond the outer of said three tubes, a movable element projecting into said open ends, said two inner tubes having at their open ends members to clampingly engage each other for gripping said element and for moving it relatively to said outer tube, and means for moving said three tubes and said element relatively to said innermost tube.

45 55 60 8. A device of the character described comprising a tube both ends of which are open, an elongate element projecting into said tube through one of the said open ends, a pair of movable elongate members projecting into said tube through the other of said openings, jaws within said tube on one of said members adapted for engaging said element and means within said tube on the other of said members adapted for actuating said jaws whereby relative movement of said members causes said jaws to clamp said element and joint movement of said members relatively to said tube moves said element relatively to said tube.

ARTHUR T. MACE.
